ADJUSTABLE RAZOR SHARPENER

George Suhayda, New York, N. Y.

Application April 8, 1938, Serial No. 200,838

2 Claims. (Cl. 51—203)

This invention relates to new and useful improvements in an adjustable razor sharpener.

More specifically, the invention proposes the construction of a razor sharpener for adjustably supporting a pair of parallel stropping elements so that they may be easily adjusted by merely turning a handle for controlling the tensioning thereof.

Still further it is proposed to so construct the device that the strop elements may be supported thereon, one with the smooth side out and the other with the rough side out for providing a choice of surfaces against which the razor may be engaged.

Still further it is proposed to characterize the razor sharpener by a pair of parallel rods having spacer plates mounted thereon, one of which is fixed and the other of which is slideable, and to stretch the strop elements between the spacer plates so that when the adjustable plate is moved it will control the tension of the strop elements.

A still further object of this invention is to provide a means whereby the strop elements may be adjusted to various tensions individually of each other.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an adjustable razor sharpener constructed according to this invention.

Fig. 2 is a perspective view of one of the strop elements per se.

Fig. 3 is a sectional view on the line 3—3 of Fig. 1.

Fig. 4 is a sectional view on the line 4—4 of Fig. 3.

Fig. 5 is a perspective view of one end of the sharpener.

Fig. 6 is an elevational view of a portion of a sharpener constructed according to a modification of this invention.

Fig. 7 is a sectional view on the line 7—7 of Fig. 6.

The adjustable razor sharpener, according to this invention, comprises parallel rods 10 and 11 having reduced end portions. The rod 10 has its ends 10^a and 10^b reduced and the rod 11 has its ends 11^a and 11^b reduced. A pair of spacer blades 12 and 13 are mounted on the shoulders

at the ends of the rods 10 and 11. The plate 12 is mounted on the reduced ends 10^a and 11^a of the rods 10 and 11. The other plate 13 is slidably mounted on the rods 10 and 11. This spacer plate 13 is adapted to be moved along the entire length of the rods 10 and 11.

A member 14 is mounted on the reduced ends 10^b and 11^b of the rods 10 and 11. The member 14 and the spacer plate 12 are adapted to hold the rods 10 and 11 in their spaced parallel positions. A pair of parallel strop elements 15 and 16 are mounted across the edges of the spacer plates 12 and 13. The strop elements 15 and 16 are constructed from lengths of leather and have their ends bent at right angles to the body portion thereof and superimposed one upon each other adjacent the outer faces of the spacer plates 12 and 13.

A means is provided on one of the spacer plates for gripping and holding one of the ends of the strop elements. The ends 15^a and 16^a of the strop elements 15 and 16 are superimposed on each other adjacent the outer face of the spacer plate 12. The reduced ends 10^a and 11^a pass through openings 15^{aa} and 16^{aa} formed in the ends 15^a and 16^a. A clamp element 17 is positioned upon the end 16^a of the strop element 16. A screw 18 passes through aligned openings formed in the center portions of the clamp element 17, the ends 15^a and 16^a and threadedly engages an opening formed in the center of the spacer strip 12. This screw 18 is adapted to be tightened for urging the clamp element 17 into a position in which it will force the ends 15^a and 16^a tightly against the outer face of the spacer strip 12.

Means is provided on the other spacer plate for gripping and holding the other ends of the strop elements 15 and 16. The ends 15^b and 16^b of the strop elements 15 and 16 are superimposed on each other on the outer face of the spacer plate 13. The end 15^b if formed with openings 15^{bb} and the end 16^b is formed with openings 16^{bb}. The rods 10 and 11 are adapted to slidably engage through the openings 15^{bb} and 16^{bb}. A clamp element 19 is slidably supported on the rods 10 and 11 and is adapted to abut against the overlapping ends 15^b and 16^b for urging these ends tightly against the spacer plate 13. A screw 20 passes freely through aligned openings formed in the member 14, the clamp element 19 and the ends 15^b and 16^b. The screw 20 threadedly engages an opening formed in the spacer plate 13. A lock nut 21 is threadedly engaged upon an intermediate portion of the screw 20.

20 and is adapted to be tightened against the clamp element 19 for urging it tightly against the ends 15^a and 16^b.

A handle 22 is mounted on one end of the 5 screw 20 for moving the slidable spacer plate 13 towards the member 14 when the handle is rotated for tightly stretching the strop elements 15 and 16 between the spacer plates 12 and 13. The handle 22 is fixedly secured at one end to 10 one end of the screw 20 and when the handle 22 is rotated in the proper direction it is adapted to move the spacer plate 13 along the length of the rods 10 and 11 away from the spacer plate 12 and toward the member 14. When the spacer 15 plate 13 moves towards the member 14 it tightly stretches the strop elements 15 and 16 between the plates 12 and 13. The handle 22 normally abuts against the outer face of the member 14 for limiting its movement with relation to the 20 rods 10 and 11.

The operation of this device is as follows:

The ends 15^a and 16^b of the strop elements 15 and 16 are securely attached between the spacer plate 12 and the clamp element 17 by engaging 25 the screw 18 through these parts. The ends 15^b and 16^a of the strop elements 15 and 16 have been slidably engaged on the intermediate portions of the rods 10 and 11 with the spacer plate inserted between the adjacent faces of the strop 30 elements 15 and 16. The clamp element 19 is then slidably engaged upon the rods 10 and 11 and the member 14 is engaged on the ends 10^b and 11^b of the rods. The screw 20 is then passed through the member 14 and the lock nut 21 positioned 35 thereon. The screw 20 is next passed through the aligned center openings of the clamp element 19 and the ends 15^b and 16^a. Then the screw 20 is threadedly passed through the center opening formed in the spacer plate 13. The handle 22 is rotated to move the spacer plate 13 away from the plate 12 for tautly stretching the strop elements between the plates 12 and 13. After the strop elements 15 and 16 have been 40 properly tensioned the lock nut 21 is rotated along the length of the screw until it tightly urges the clamp element 19 against the ends 15^b and 16^a of the strop elements—the sharpener is then in position for sharpening a razor.

If the strop elements 15 and 16 should stretch 45 or become loose between the plates 12 and 13 they may be further tensioned by moving the lock nut 21 out of contact with the clamp element 19 and then the handle 22 may be again rotated to space the plate 13 further away from the plate 12 to again tension the strop elements to compensate for the stretching.

According to the modification shown in Figs. 6 and 7 a provision is made for adjusting the strop elements 15 and 16 individually of each 50 other. This means comprises a strip element 60 23 adjustably mounted on one edge of the plate 13 and engageable against the strop element 15 for tightening the strop element 15 to a greater degree than the strop element 16. The adjustable supporting of the strip element 23 comprises lugs 24 formed upon the strip element. These lugs 24 are integrally formed with screws 25 which are adapted to slidably engage through lugs 26 formed on the plate 13 immediately below the lugs 24. The lugs 26 are formed with openings 26^a through which the screws 25 are slidably engaged. Nuts 27 are threadedly engaged upon an intermediate portion of the screws 25 and are adapted to abut the top face of the lugs 26 for 65 holding the screws 25 in various adjusted posi-

tions with relation to the lug 26 for moving the strip 23 away from the plate 13. Lock nuts 28 are threadedly engaged upon the ends of the screws 25 and are adapted to abut the bottom end of the lugs 26 for fixedly holding the screws 5 in their adjusted positions.

The operation of this form of the device is as follows:

After the handle has been rotated to tension the strop element 16 to the desired degree the 10 strop element 15 may be further adjusted to tighten it to a greater degree than the strop element 16. This is accomplished by inserting a small nut wrench between the strop elements 15 and 16 and loosening the lock nuts 28. The 15 wrench is then used for rotating the nuts 27 to extend the screws 25 with relation to the lugs 26. These screws 25 are fixedly attached to the lugs 24 and when the nuts 23 are rotated they will 20 extend the screws 25 causing the strip element 23 to move away from the plate 13 to tension the strop element 15 to a greater degree than the strop element 16. In other respects this form of the invention is similar to the previous form.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An adjustable razor sharpener, comprising 35 a pair of parallel rods having reduced end portions, a pair of spacer plates one being mounted on the shoulders at one of the ends of said rods and the other being slidably mounted on the rods, a member mounted upon the other shoulders of 40 said rods, a pair of parallel strop elements mounted across the edges of said plates, means on one of the spacer plates for gripping and holding one of the ends of said strop elements, means on the other of said spacer plates for 45 gripping and holding the other ends of said strop elements and including a screw threadedly engaging through the spacer plate and a nut thereon, and a handle abutting said member when said handle is rotated to tightly stretch said strop elements between said spacer plates, and a strip element adjustably mounted on one of the edges of 50 one of said spacer plates for permitting one of said strop elements to be tightened to a greater degree than the other of said strop elements, said means for adjustably mounting said strip element comprising lugs formed on said strip element, screws fixedly attached to said lugs, lugs formed on said spacer strip and having openings through which said screws freely pass, nuts 55 threadedly engaged upon an intermediate portion of said screws and abutting against the top end of said lugs on said spacer plate for holding said screws in various adjusted positions to move said strip element away from said spacer plate, and means for holding said screws fixed in their adjusted positions.

2. In a device of the class described, means for tautly stretching a pair of parallel strop elements, including a fixed plate disposed laterally of said strop elements and upon which one of the ends of said strop elements are mounted, a movable plate disposed laterally of said strop elements and upon which the other of the ends of said strop elements are mounted and being mov- 75

able away from the fixed plate for stretching said strop elements, and a strip element adjustably mounted on one of the edges of one of said plates and movable transversely away from or toward the edge upon which it is mounted to tighten or loosen one of said strop elements in relation to the other, said adjustable mounting of said strip element, comprising lugs formed on said strip element, complementary lugs formed on the adjacent edge portion of the plate supporting said strip element, screws having one of their ends fixedly attached to said first-mentioned lugs and the other of their ends passing

freely through openings formed in the other of said lugs, and nuts threadedly engaged on said screws between the adjacent faces of said lugs and engageable against said latter-mentioned lugs for holding said screws to various distances with relation to said latter-mentioned lugs to correspondingly hold said strip element, and nuts engaged upon the free ends of said screws for preventing said screws from being entirely disengaged from the openings in said latter-mentioned lugs. 5 10

GEORGE SUHAYDA.
